Des. 224,744
Patented Sept. 12, 1972

224,744

TOY AUTOMOTIVE VEHICLE

Norman Spiegel, New York, N.Y., assignor to
Nasta Industries, Inc.

Filed Apr. 5, 1971, Ser. No. 131,286

Term of patent 14 years

Int. Cl. D21—01

U.S. Cl. D34—15

FIG. 2

FIG. 3

FIG. 1 is a top, front and left side perspective view of a toy automotive vehicle showing my new design; FIG. 2 is a right side elevational view thereof; and FIG. 3 is a rear elevational view thereof.

I claim:

The ornamental design for a toy automotive vehicle, as shown.
